SANITARY DRY CLOSET

Filed March 27, 1930

UNITED STATES PATENT OFFICE

JOSEPH LUTHER HART, JR., OF CHICKASHA, OKLAHOMA

SANITARY DRY CLOSET

Application filed March 27, 1930. Serial No. 439,430.

This invention relates to dry closets, familiarly known as outdoor toilets, and is designed to render them sanitary through pit closure and external ventilation.

An object of the invention is to provide a closet of this type having a pit fully closed when the toilet is not in use, with an outside vent communicating with the pit and forming the only means of fume exit and acting automatically to exhaust heated vapors therefrom, causing a suction inducing downward leakage of cold air through pit closure joints on the interior of the toilet to create interior fume preventing circulation or draught outwardly and externally. By fully closing the pit when not in use, all heated generated therein is made effective to cause upward flow of heat vapor through the outside vent, with the interior of the closet maintained free from fumes.

A further object of the invention is the provision of a toilet hopper having a closure valve below the seat with means for automatically moving said valve to pit closing position when the seat is not in use.

These and other objects and the structural features through which they are attained will be more clearly apparent from the following detailed description which is to be read in conjunction with the accompanying drawings forming part thereof and in which:

Figure 1 is a transverse sectional view through a closet and pit constructed in accordance with the present invention, including the outside vent and its connection to the pit, the valve being shown in closed position.

Figure 2 is a longitudinal vertical section on an enlarged scale taken on line 2-2 of Figure 1, but with the seat and valve only partially lifted.

The closet in its entirety is shown in Figure 1 in which its roof 1 overlies and its walls 2 enclose a pit 3, dug, for example, in the earth, and completely over laid by the floor 4 of the closet, which may be of metal, for example, and provided with a hopper opening 5 therein overlying the pit 3 and edged by a depending flange 6.

A hopper 7 which may be of metal, is preferably, as shown, provided with a vertical

front wall 8, outwardly diverging side walls 9, and an outwardly diverging rear wall 10, each provided at their lower end with an outturned flange 11 with the enlarged area of the lower end of the hopper slightly greater than and conforming in contour with that of the hopper opening 3 in the floor so that the flanges 11 will rest upon the floor at the edge of the opening 3 and may be bolted thereto as shown to provide a substantially air tight junction therewith.

The open top of the hopper has applied thereto a cover plate 12 having downturned edge flanges 13 embracing the top of the hopper sides, and is provided, additionally, with an opening 14 therein overlaid by a seat 15 hingedly mounted at its rear end by the upper arms 16 of a pair of L-shaped hinge straps to the cover plate 12 at the rear edge of its opening 14. The lower arms 17 of these hinged straps are attached to the upper face of a valve plate 18 at its rear edge. This valve plate is shaped to have its marginal edges slightly overlap the edges of the opening 14 when abutting thereagainst. An arm 19 is rigidly connected with one side of this plate at its rear edge and extends downwardly therefrom. A coiled tension spring 20 has one end anchored to the lower end of arm 19 and extends at the outer side of the side of the plate forwardly to the forward end of the hopper where it is anchored to the under face of the cover plate 12 at a point beyond the area of contact of the marginal edge of the valve plate therewith. The tension of this spring is normally effective to act against the valve plate and hinged straps 16-17 to swing the valve plate upwardly to contact the edges of the opening and close communication between the pit and the hopper above the valve plate, and coincidently to swing the seat upwardly as shown in Figure 1.

When the seat is pressed downwardly and weight is superimposed thereon the L-shaped hinge arms 16-17 will coincidently swing the valve plate 18 downwardly and hold the hopper open and in communication with the pit so long as weight is superimposed on the seat 15.

With the seat not in use and raised through the spring the pit is closed against the exit of fumes upwardly therefrom, and any slight leakage of air around the valve seat and through the base joint of the hopper with the flooring is utilized to create venting circulation outwardly from the pit to the exterior of the closet. To this end, a tubular vent pipe 21, preferably rectangular in cross section to facilitate the connection of a lateral pit venting extension thereto, upstands from the earth or floor externally of the closet structure and may be supported in upright position by any suitable means, as by the brace 22 extending outwardly from the side 2 of the closet frame. The lower end of this vent pipe is open and imbedded in the earth a substantial distance to provide a drain into the earth for any liquid entering the pipe, such as rain, snow and sleet, condensation, etc. From a point above the lower end of the upstanding vent pipe, and below the top of the pit opening, a lateral imbedded vent 23 of similar cross section extends from an end 25 of communication with pipe 21 laterally through the earth to enter and communicate with the interior of the pit opening adjacent but below its top. The lateral vent is preferably supported from the flooring 4 by a suitable depending bracket 24 or reliance may be placed, if desired on the maintenance of the support by the earth or other substance in which it is imbedded.

The vertical pipe 21 and its lateral extension 23 are preferably of rectangular cross section since this facilitates a tight junction. The internal cross sectional area of both the vertical vent 21 and lateral 23 are intended to be substantially greater than the area of any air leaking crevices which may exist, theoretically, between the valve and hopper with the former closed. Consequently with the pit closed at the side by the imbedded lateral and at the top of the hopper valve, substantially all gases generated in the pit will follow the larger escape opening and vent through the lateral and vertical vent tubes 23 and 21 to atmosphere externally of the closet, and any crevices that may exist in the hopper and floor and hopper and valve joints will aid this venting movement by causing cold air to pass downwardly therethrough forcing an outward and upward external venting of the warmer air and vapors in the pit. No air or fumes, therefore, will pass upwardly through the hopper joints with the hopper valve closed and constant outward venting circulation of air and fumes to a point externally of the closet will take place.

I claim:

1. A dry closet having a pit, a hopper having its base seated over and enclosing the top of said pit, a top closure for said hopper having an opening therein, a pair of hinge mem-

bers mounted at the rear of said opening and each having angularly disposed leaf members, a seat connected to one leaf of said hinge, a valve connected to said other leaf, said seat and valve being arranged for alternate engagement with said top closure, said valve being of a size to completely close the opening in said top closure when positioned therebeneath, and resilient means for holding said valve in closed relation with said top upon movement of said seat to raised inoperative position.

2. A dry closet having a pit, a hopper having its base seated over and enclosing the top of said pit, a top closure for said hopper having an opening therein, a pair of hinged members mounted at the rear of said opening and each having angularly disposed leaf elements, a seat connected to one leaf of said hinge, a valve connected to said other leaf, said seat and valve being arranged for alternate engagement with said top enclosure, said valve being of a size to completely close the opening in said top closure when positioned therebeneath, a rigid arm carried by said valve, and a tension spring secured between said arm and a forward portion of said top closure whereby to alternately swing said valve in closed relation with said top.
